UNITED STATES PATENT OFFICE.

EDWARD I. HUFF, OF PHILADELPHIA, PENNSYLVANIA.

SAFETY DEVICE FOR LADDERS.

1,373,133.

Specification of Letters Patent. Patented Mar. 29, 1921.

Application filed May 14, 1919. Serial No. 297,031.

To all whom it may concern:

Be it known that I, EDWARD I. HUFF, a citizen of the United States, and a resident of Philadelphia, county of Philadelphia, State of Pennsylvania, have invented certain new and useful Improvements in Safety Devices for Ladders, of which the following is a specification, reference being had to the accompanying drawings.

10 My invention relates particularly to that class of devices that are employed in connection with ladders or other climbing apparatus, and is especially directed to hand-actuated mechanism coöperative with means 15 carried by the ladder to prevent the climber from falling therefrom.

The principal objects of my invention are to provide a ladder with means so coöperative with movable hand-grips carried by the 20 climber as to permit their free normal movement effected by the climber in ascending or descending, but which will automatically catch and retain the climber should he fall.

Other objects of my invention are to provide 25 a ladder with run-ways on the side-rails thereof, with which hand-grips may be slidably engaged in such relation as to be inseparable therefrom while in use, and to provide said hand-grips with means for attaching them to the climber.

30 My invention also comprehends a station so connected with the run-way that a plurality of hand-grips may be held ready for the use of different climbers, and said station 35 may be constructed to include as many hand-grips as there are climbers likely to ascend the ladder.

The form of my invention as hereinafter described comprises a ladder having its 40 hand-rails provided with tubular run-ways, each having a slot with one edge smooth or straight and the other edge notched, and a hand-grip provided with wristlets arranged to engage the wrist of the climber, and having 45 a shank extended through said slot and retained therein by an enlarged flange within said run-way, said shank being free to slide up and down said slot unless drawn into engagement with the notches by any 50 abnormal movement of the climber, as by his tending to fall.

55 My invention also includes all of the various novel features of construction and arrangement as hereinafter more definitely specified.

In the accompanying drawings, Figure 1

is a side elevational view of a ladder conveniently embodying my invention as applied to a chimney or stack; Fig. 2 is a front elevational view of the ladder shown in Fig. 60 1; Fig. 3 is an enlarged fragmentary front elevational view showing in detail the right hand side-rails of a ladder having a tubular run-way attached, and a hand-grip engaged in a notch in the run-way slot; Fig. 4 is a 65 fragmentary side elevational view of the structure shown in Fig. 3; and Fig. 5 is a plan sectional view taken on the line 5—5 in Fig. 4.

In said figures the ladder comprising the 70 side-rails 1, rungs 2, and run-ways 3, may be applied as shown in Fig. 1, to a stack or chimney 5, or may be adapted to any structure where a ladder is required. Said run-ways 3 may preferably extend above the top 75 of the chimney and be continued horizontally as shown, being connected thereto by the angle-iron supports 6 and 7.

The run-ways which may be preferably formed of rectangular tubes are each provided 80 with a continuous slot 9 in its lateral wall 10, having its inner edge 11 extending uninterruptedly parallel with its longitudinal axis, and its outer edge provided with a series of regularly spaced 85 notches 12 as shown in Figs. 1 and 4.

The run-ways 3 are provided with hand-grips comprising the yoke 13, carrying the handle 15, and having the shank 16 extending through the slot 9, and provided within 90 the run-way 3 with an enlarged head 17 preferably in the form of a circular disk arranged to prevent the displacement or removal of the hand-grips while in use.

Said hand-grips are provided with wristlets 95 20 preferably formed of a leather strap and loosely but securely connected with the base of the yoke 13 by the ring or link 21, engaging the eye 22 on said base. The wristlets 20 are looped in the form of a 100 noose having its outer terminal provided with a ring 23 embracing the strap and providing a loop 25 through which the hand may be passed to grip the handle 15.

It will be obvious from the foregoing description that the climber, having attached the wristlets 20 to his wrists, and grasped the handles 15 of the hand-grips upon the opposite sides of the ladder, may readily ascend or descend said ladder by sliding the 110 shanks 16 of the hand-grips up or down the slots 9 of the run-ways 3, and that should

he misstep or tend to fall backward the shanks 16 will engage the nearest notch 12 and thereby arrest further movement thereof and retain him from descending farther 5 until he releases said shank from said notch.

Moreover, the climber is not dependent upon the rungs of the ladder for his ascension, for obviously, if any of the rungs were missing or even were there no rungs he 10 could readily climb by alternately engaging the shanks 16 of the respective hand-grips with the notches 12, and thereby draw himself up by hand. This is especially advantageous in connection with telephone, telegraph, light or flag poles, wherein it is undesirable to provide means for climbing capable of being used by mischievous persons or minors.

It may be here noted that the run-ways 3 20 may form the side-rails of a ladder, as is shown in the upper portion of Fig. 2, or that said run-ways 3 may be applied or attached to the side-rails 2 of a ladder by bolts 26, as shown in Figs. 3, 4 and 5, in which 25 event the lateral wall 10 of the run-way is provided with apertures 27 registering with apertures 29 in the opposite wall, through which the bolts 26 may be passed.

As shown in Figs. 1 and 2, the run-ways 30 3 may terminate in terminal stations 30 for the hand-grips when not in use, said stations each comprising a hollow casing having its outer wall 31 provided with a slot 32 registering with, and forming a continuation of the slot 9, and having a plurality of spurs 33, extending laterally therefrom, into which the shank 16 of the hand-grip may be slid, as best shown in Fig. 1, it being understood that although but one pair of hand-grips are shown in the station, each of the spurs 33 may have hand-grips therein ready 40 for use.

The stations may, if desired, be provided with covers 35 hingedly connected therewith, and may be locked to prevent unauthorized persons from tampering with the hand-grips in said stations, the cover on the left of Fig. 2 being shown open and the cover on the right of said figure being shown 45 closed for convenience of illustration.

I do not desire to limit my invention to the precise details of construction and arrangement as herein specified, as it is obvious that various modifications may be

made therein without departing from the 55 essential features of my invention as defined in the appended claims.

Having thus described my invention, I claim:

1. In a climbing apparatus, the combination with a tubular run-way provided with a slot having a straight edge and a notched edge, of hand-grips operated by the climber, arranged to freely slide and rotate in said slot, in engagement with said straight edge, 60 but automatically arrested by the notches of the notched edge, and retained thereby, upon downward movement of said gripping means away from said straight edge.

2. In a climbing apparatus, the combination with a run-way having a slot provided with a notched edge, of hand-grips having means coöperative with the notches in said run-way to prevent the climber from falling, and a station for said hand-grips having a slot registering with the slot in said run-way, and provided with spur slots extending laterally from said slot, for the reception of said gripping means. 75

3. In a climbing apparatus, the combination with a run-way having a slot provided with a notched edge, of gripping means coöperative with the notches in said run-way to prevent the climber from falling, and a station for said gripping means, having a slot 80 registering with the slot in said run-way, and provided with spurs extending laterally from said slot, for the reception of said gripping means, and a cover for said station.

4. A ladder having its side-rails provided with run-ways having each a slot provided with a notched edge, and a hand-grip coöperative with each of said run-ways to prevent the climber from falling, comprising a handle, a shank extended through said slot engageable with the notches of said notched edge, and a flanged head on said shank within said run-way to prevent the displacement of said hand-grip from said run-way while 95 in use.

In witness whereof, I have hereunto set my hand and seal this 13th day of May, A. D. 1919.

EDWARD I. HUFF. [L. s.]
